Inventor,
John Landers.

Att. Attorney

UNITED STATES PATENT OFFICE.

JOHN LANDERS, OF LEBANON, NEW HAMPSHIRE, ASSIGNOR TO H. W. CARTER & SONS,
OF LEBANON, NEW HAMPSHIRE, A FIRM COMPOSED OF A. H. CARTER AND H. B.
JACKSON.

COMBINED STRAP AND WAISTBAND.

1,244,403.

Specification of Letters Patent. Patented Sept. 25, 1917.

Application filed May 22, 1917. Serial No. 170,215.

To all whom it may concern:

Be it known that I, JOHN LANDERS, a citizen of the United States, residing at Lebanon, in the county of Grafton, State of New Hampshire, have invented certain new and useful Improvements in Combined Straps and Waistbands, of which the following is a description, reference being had to the accompanying drawings, forming a part hereof.

My invention relates to overalls and like union garments for outside wear and particularly to overalls for women's wear and my invention has for its object to provide a combination strap and waist band adapted for use with and forming part of such garment which will be simple, inexpensive and strong and will also serve to form a high back for the garment.

With this object in view my invention consists in the construction and combination of elements hereinafter described and claimed.

Referring to the drawings:

Figure 1 is a front view of a pair of overalls provided with the combination strap and waist band embodying my invention.

Fig. 2 is a back view of the same and Fig. 3 is a detail view of the two straps.

In the drawings 1 indicates the leg portion of the overalls which in the construction shown are made quite full and are provided near their lower ends with plaits 2 secured to straps or bands 3 and having side

openings 4 extending from the waist band down along the hips toward the knees and provided with suitable fastening devices 5. The front portion of the waist band extending across the front of the garment from one side opening 4 to the other is of usual construction and above this portion of the waist band is a bib 7. The construction thus far described forms no part of my present invention and may be as shown or may be varied in accordance with any usual construction of such garments.

The back portion of the waist band, that is the portion extending along the waist line at the back from one side opening 4 to the other is formed of two L-shaped pieces 10 and 11 of material each consisting of an upright or strap portion 12 and a horizontal or waist band portion 13 the two portions

being arranged at an obtuse angle one with the other as shown the outside lines of the two portions coming together at an obtuse point 14 and the inside lines forming a curve as shown at 15. The two pieces 10 and 11 are identical in shape but the face of the material and the finishing of one is so arranged that its upright or strap portion will extend in one direction and the upright or strap portion of the other will extend in the other direction as shown and the horizontal or waist band portion will likewise extend in opposite directions. The two pieces suitably hemmed or otherwise finished along their edges and provided in their upright portions with button holes 16 and 17 are placed one over the other with the upright or strap portions pointing outward in different directions as shown and with the horizontal or waist band portions likewise extending in opposite directions and the two pieces are stitched or otherwise secured together as by lines of stitching 18 and the back portion of the waist band formed by the portions 13 of the two pieces is then secured to the garment.

The button holes 16 and 17 are adapted to be engaged with buttons 20 on the bib 7. The straps being integral with the back portion of the waist band cannot be detached and the portion of one piece which overlies the other forms above the points 14 a high back to protect the wearer of the overalls.

The two pieces 10 and 11 being of the same shape may both be cut by the same pattern though the material of course in cutting one will be so arranged that its face will be upward and for the other will be downward or if not cut at the same time the pattern after one is cut may be simply turned over for cutting the other. By suitably arranging the patterns the pieces may be cut from the material with very little waste.

The combined strap and waist band thus formed may be used with any form of garment in which suspender straps are used. The angle of the strap and waist band portion to each other may be varied as desired and the curve of the inner lines may be varied to make the vertical line extending upward from the points 14 longer or shorter

as may be desired so as to make the back formed by the overlying portions more or less high as desired.

Having thus described my invention what 5 I claim is:

1. The herein described combined strap and waist band consisting of two substantially L-shaped pieces of material crossing one over the other and secured together 10 at the junction of the strap and waist band portions.

2. The herein described combined strap and waist band consisting of two substantially L-shaped pieces of material crossing one over the other and secured together 15 at the junction of the strap and waist band portions the inner lines being curved to afford a high back.

In testimony whereof I affix my signature this 9th day of May, 1917.

JOHN LANDERS.
